UNITED STATES PATENT OFFICE.

WILLARD H. PARROTT, OF LOS ANGELES, CALIFORNIA.

CLIP GUIDE.

Application filed July 10, 1922. Serial No. 573,930.

To all whom it may concern:

Be it known that I, WILLARD H. PARROTT, a citizen of the United States, residing at Los Angeles, county of Los Angeles, State of California, have invented new and useful Improvements in Clip Guides, of which the following is a specification.

This invention relates to means for positioning the blank sheets of paper fed onto the platen of a printing press.

It is the object of the invention to provide guide clips, which may be readily clamped in adjusted position upon the usual clamped in adjusted position upon the usual top sheet received upon the platen of a press, top sheet received upon the platen of a press, 10 the platen of a printing press.

15 the clips forming abutment elements against which the blank sheets of paper are fed, in order to properly position the paper during the printing operation.

It is a further object of the invention 20 to provide spring fingers which may be employed in conjunction with the clips, so that the fingers will hold the sheets of paper down on the top sheet, as the paper is fed against the abutment elements. The sheets 25 of paper are thus prevented from becoming disarranged by sliding over the clips.

Further objects of the invention will be readily understood from the following description of the accompanying drawings, in 30 which:

Fig. 1 is a plan view of a corner of a top sheet showing the improved guide clips mounted thereon.

Fig. 2 is a detail section on the line 2—2 35 of Fig. 1.

Fig. 3 is perspective view of one of the guide clips.

In printing upon a usual platen press, a packing pad is placed upon the platen, and 40 a top sheet as shown at 1 in the drawings, is received upon the pad. In the present invention, guide clips are detachably and adjustably clamped upon the top sheet, so as to form abutments for positioning the sheets 45 of paper upon which the printed impression is to be made.

One of these guide clips is shown in detail in Fig. 3, and comprises a blank of any suitable material, preferably metal. The blank 50 consists of a base 2, which at its front is bent upwardly and then downwardly, to form the vertical abutment surface 3. A pair of spaced ears 4 extend laterally from either side of base 2, beyond the abutment 55 surface 3. At the sides of the rear of the base are depending prongs 5, and upstand-

ing lips 6, which latter are substantially in alinement with the ends of surface 3, and the inner ends of ears 4.

A spring strip 7 extends across the clip 60 upon base 2, and in alinement with the notches 8 formed between the ears of each pair at the sides of the clip. The spring may be retained in position by overlying lips 10 stamped from the base 2.

The end portions of the spring are bent 65 downwardly into notches 8 as shown at 11, and are then reversely bent upon themselves as shown at 12. These reversely bent ends terminate in upturned gripping means 13 70 adapted to be grasped in the fingers for manipulating the spring.

The clip may be used in the form thus 75 described, but preferably, spring fingers are arranged upon the clips, so as to project forwardly beyond said clips.

Each of these fingers consists of a spring strip 15, curved upwardly slightly at its forward end. The fingers may be positioned at one or both sides of the clips, and extend 80 across ears 4 and project forwardly beyond the abutment surface 3. The fingers lie upon the end portions of spring 7, and beneath the reversely bent portions 12 of the spring, with the rear ends of the fingers in 85 lateral abutment against lips 6.

It will thus be seen that the fingers will 90 be held in position by the spring, while permitting the ready removal or longitudinal adjustment of said fingers.

In using the improved clip guides, markings 14 for the edges of the sheets of paper to be printed, are made upon top sheet 1, in usual manner. Pairs of slits 16 are then 95 cut in the top sheet wherever it is desired to place one of the guides. The slits of each pair extend from a marking 14 toward the outer edge of the top sheet, and preferably divergently curve as clearly shown in Fig. 1.

A clip is positioned upon the top sheet 100 between the slits of a pair, with ears 4 inserted through said slits beneath the top sheet, it being understood that the slits are suitably spaced to accommodate the clip in this position.

As the clip is thus positioned, the ends of 105 spring 7 are lifted by compressing the gripping means 13, so that said spring ends will rest upon the upper surface of the top sheet.

The clip is adjusted lengthwise of the slits until the abutment surface 3 is at the mark-

ing 15, and the spring is then released so that the ends 11 thereof will clamp the clip upon the top sheet. When the clip is in position, the prongs 5 are also forced into the top sheet to further insure the retention of the clip in its adjusted position.

With the clip positioned as thus described, the lower edge of abutment surface 3 rests upon the top sheet between slits 16, and the 10 portions of the top sheet beyond the slits are elevated slightly upon ears 4. As a consequence, when the edge of a sheet of paper fed onto the top sheet, abuts against surface 3 for properly positioning the paper, it 15 will be raised slightly by the portions of the top sheet beyond the slits, and the possibility of the sheet of paper catching in the crack between surface 3 and the top sheet, is thus eliminated.

20 The spring fingers 15, when employed, extend beyond surface 3, and will thus slip over a sheet of paper fed onto the top sheet and abutting against the guide clips, so as to hold the paper down on the top sheet, and 25 prevent the same sliding over the clips.

While I have illustrated and described but one practical embodiment of the device, it will be apparent that various changes may be made in the construction, combination, 30 and arrangement of parts, without departing from the spirit of the invention.

What is claimed is:

1. A clip of the character described comprising a base forming a front abutment 35 surface and having ears extending laterally beyond said surface with the front edges of said ears in alinement with said surface, said base being adapted to be received upon a printing press top sheet with said ears extending through and beneath the same.

2. A clip of the character described comprising a base forming a front abutment surface and having ears extending laterally beyond said surface with the front edges 45 of said ears in alinement with said surface, said base being adapted to be received upon a printing press top sheet with said ears extending through and beneath the same, and means for clamping said base on said top sheet.

3. A clip of the character described comprising a base forming a front abutment surface, means extending laterally beyond said abutment surface for clamping said 55 base upon a printing press top sheet, and a spring finger carried by said laterally extending clamping means and extending forwardly beyond the side of said abutment surface above said top sheet.

60 4. A clip of the character described comprising a base adapted to rest upon a printing press top sheet and forming an abut-

ment surface, said base having spaced ears extending beyond the same and adapted to project through said top sheet and beneath the same, and a spring on said base having its end extending between said ears and tending to press downwardly so as to clamp against said top sheet.

5. A clip of the character described comprising a base forming a front abutment surface and having ears extending laterally beyond the sides of said abutment surface, said base being adapted to be received upon a printing press top sheet with said ears extending through and beneath said top sheet so as to elevate the portions of said top sheet in transverse alinement beyond the sides of said abutment surface.

6. A clip of the character described comprising a base forming a front abutment surface and having an upturned lip at the rear thereof, spring means for clamping said base on a printing press top sheet, and a finger fixed on said base by said spring means and extending forwardly beyond said abutment surface with its rear end abutting transversely against said lip.

7. A clip of the character described comprising a base adapted to rest upon a printing press top sheet and forming an abutment surface, said base having lateral extensions adapted to be received through and beneath said top sheet, and a spring on said base with its ends adjacent said lateral extensions and terminating in reversely bent portions forming manual gripping means.

8. A clip of the character described comprising a base forming a vertical abutment surface at the front thereof, laterally extending ears adjacent said surface, and depending prongs at the rear of said base, and a spring fixed upon said base with its ends alongside said ears.

9. A clip of the character described comprising a base forming a vertical abutment surface at the front thereof, laterally extending ears adjacent said surface, and upturned lips at the rear of said base in alinement with the inner portions of said ears, a spring fixed upon said base with its ends alongside said ears and terminating in reversely bent portions forming manual gripping means, and fingers projecting forwardly beyond said abutment surface above 115 said ears with the rear ends of said fingers in lateral abutment against said upturned lips, said fingers being received upon the respective ends of said spring beneath the reversely bent portions thereof.

In testimony whereof I have signed my name to this specification.

WILLARD H. PARROTT.
